UNITED STATES PATENT OFFICE.

FREDERICK E. MARTIN, OF BONAMI, LOUISIANA, ASSIGNOR TO SECURITY EQUIPMENT COMPANY, A FIRM COMPOSED OF HIMSELF, J. HERMAN McMAHON, OF DE RIDDER, LOUISIANA, AND ROY F. MORSE, OF BEAUMONT, TEXAS.

RETAINING-VALVE.

1,076,135.

Specification of Letters Patent. Patented Oct. 21, 1913.

Application filed June 29, 1912. Serial No. 706,806.

To all whom it may concern:

Be it known that I, FREDERICK E. MARTIN, a citizen of the United States, residing at Bonami, in the parish of Calcasieu and 5 State of Louisiana, have invented certain new and useful Improvements in Retaining-Valves; and I do hereby declare the following to be a full, clear, and exact description of the invention, such as will enable others 10 skilled in the art to which it appertains to make and use the same.

My invention relates to improvements in retaining valves, and it consists in the constructions, combinations and arrangements 15 herein described and claimed.

An object of my invention is to provide an improved retaining valve for air-brake systems, in which a reduction of the train-pipe pressure below a predetermined point will insure the brakes remaining set until the train-pipe system has been recharged to bring the 20 pressure above such predetermined point.

In the accompanying drawings forming a part of this application, and in which similar reference symbols indicate corresponding parts in the several views:—Figure 1 is 25 an axial section on the line 1—1 of Fig. 2, illustrating one embodiment of my invention; and Fig. 2 is a section on the line 2—2 of Fig. 1.

Referring to the drawings, 1 indicates a casing which is divided by a diaphragm 2 into a pressure chamber 3 and an exhaust chamber 4 provided with an exhaust outlet 35 5. The usual triple-valve exhaust pipe 6 is connected to a chamber 7 communicating with said chamber 4, and an extension 8 from said pressure chamber 3 is connected to the train-pipe or to the usual auxiliary air 40 reservoir.

A retaining valve 9 controls the communication between the triple-valve exhaust pipe and the exhaust chamber 4; said valve being normally seated by a spring 10 bearing 45 against a disk 11 which can be adjusted by a bolt 12 for varying the tension of said spring to meet all different service conditions.

A spindle 13 is secured to the diaphragm 50 2 in position for engaging said retaining valve 9 to unseat the latter, and a valve 14 is secured on said spindle in position to close a port 15 for cutting off the train-pipe pressure from said pressure cylinder 3; a spring

16 engaging a stop 17 adjustably mounted 55 on said spindle for yieldingly seating said valve 14 and maintaining said spindle out of engagement with the retaining valve 9. The spindle 13 is provided with a bore 18 opening into said chambers 3 and 4, and 60 adapted to be closed by the retaining valve 9 when said spindle is maintained in engagement with said valve.

In the operation of my invention, the train-pipe pressure in the pressure chamber 65 3 normally presses the diaphragm 2 outwardly, and causes the spindle 13 carried by said diaphragm to hold the retaining valve 9 from its seat; thereby establishing communication between the triple-valve exhaust 70 pipe 6 and the exhaust opening 5 and maintaining the brakes released. If the engineer now reduces the train-pipe pressure, the springs 10 and 16 will force the diaphragm inward against the reduced pressure 75 in the chamber 3, and the retaining valve will be seated to close communication of the triple-valve pipe 6 with the exhaust opening 5; the reduced pressure in the chamber 3 acting on the diaphragm to maintain the 80 valve 14 open and the spindle 13 in engagement with the seated retaining valve. In this position of the parts, an increase in the train-pipe pressure will act on the relatively large diaphragm 2 to unseat the retaining 85 valve 9 for permitting release of the brakes. Should the train-pipe pressure be further reduced below a predetermined point, the spring 16 will close the valve 14 and withdraw the spindle 13 from engagement with 90 the retaining valve; thereby permitting the air under pressure in the chamber 3 to escape through the spindle bore 18 to the exhaust opening 5. In this position of the parts, the pressure in the train-pipe will be 95 effective only on the closed valve 14, which is of less area than the diaphragm 2; thereby insuring the brakes remaining firmly set until the train-pipe pressure has been again raised sufficiently high to force the valve 100 14 open against the tension of the spring 16.

From the above description, it will be clear that my invention provides a compact and strong retaining valve for air-brake systems which will operate with certainty under all service conditions.

I have illustrated and described preferred and satisfactory constructions, but changes

could be made within the spirit and scope of my invention.

I claim:-

1. In an air-brake mechanism, a casing, a diaphragm dividing said casing into a pressure chamber and an exhaust chamber provided with an exhaust opening, means for placing the usual train-pipe and triple-valve exhaust pipe in communication with such pressure and exhaust chambers, respectively, a retaining valve controlling the communication of the triple-valve exhaust pipe with such exhaust chamber, and a spindle carried by said diaphragm for actuating said retaining valve, said spindle being provided with a bore opening at the opposite sides of said diaphragm and controlled by said retaining valve.

2. In an air-brake mechanism, a casing, a diaphragm dividing said casing into a pressure chamber and an exhaust chamber pro-

vided with an exhaust opening, means for placing the usual train-pipe and triple-valve exhaust pipe in communication with such pressure and exhaust chambers, respectively, a retaining valve controlling the communication of the triple-valve exhaust pipe with such exhaust chamber, a spindle carried by said diaphragm for actuating said retaining valve, said spindle being provided with a bore opening at the opposite sides of said diaphragm and controlled by said retaining valve, and a valve of less area than said diaphragm secured to said spindle for controlling communication of the train-pipe pressure with such pressure chamber.

In testimony whereof, I affix my signature, in presence of two witnesses.

FREDERICK E. MARTIN.
